UNITED STATES PATENT OFFICE

WILFORD E. BURNS, OF BURLINGAME, CALIFORNIA, ASSIGNOR TO M. J. B. CO., OF SAN FRANCISCO, CALIFORNIA, A CORPORATION OF DELAWARE

KEY-OPENING CAN

Application filed November 26, 1927. Serial No. 235,779.

This invention relates to key-opening tin cans as provided with a tearing strip for engagement with a winding key, and the objects of the invention are to provide improvements in the temporary fastening of the key to the can top so that it will be readily accessible to a person desiring to open the can, yet will not be liable to become loose or lost from the can top, also such a construction which will contribute to easier manufacturing operations in making the can complete with its key.

In the drawings hereto the upper head or lid only of a can is shown with my improved key feature, as the particular construction of the body of the can is immaterial to this invention.

Fig. 1 is a plan view of the can lid showing a special depression for receiving the key.

Fig. 2 is a similar plan view to Fig. 1 but with the key in place and tip end soldered to lid.

Fig. 3 is a cross section of the lid as seen from the line 3—3 of Fig. 2.

In further detail the lid is designated 1, the key receiving depression 2, and the key 3.

This lid is shown with an annular marginal recess 4 to provide an internal friction lid for the can, and the key depression is so formed that its inner end lies in the center of the lid circle and is formed with a small step at 5 to support the tip only of the key, with the bottom of the depression spaced below the shank of the key as shown at A in Fig. 3.

The body of the key lies substantially flush with the upper surface 1 of the lid and the depression is provided with a raised portion or hump 6 fitting freely within the loop or handle 7 of the key so-shaped as to support the handle end of the key in alignment with the small step 5 at the tip of the key.

The extreme tip of the key is soldered to the lid with a drop of solder as at 8 and since the end of the key rests only on the step in a narrower portion of the depression it is manifest that the soldered area cannot

extend variously along the key shank but will always be limited to exactly the area of the step, even though a little of the solder should run beyond the step since the depression clears the key at the sides at B and under the key at A.

Extending laterally from the raised portion or hump 6 are two deepened depressions 9 adapted to facilitate grasping the key with the fingers and tearing it loose from the tip end.

Also it should be observed that the small step 5 supporting the tip of the key lying in the center of the can circle is easily soldered by an automatic tipping machine regardless as to the angular extension of the key. This also provides for soldering the key and tipping the can simultaneously in cases where the can contents are vacuumized through an aperture punched through the can lid, it being merely necessary to punch such an aperture through the step 5 before placing the key in the depression.

The hump 6 is a valuable feature of the improvement as it is a tapering free fit within the handle or bail of the key so that a key dropped at random within the depression or merely upon the lid and the lid shaken will automatically fall into the only position available to it, and which of course is the correct position as shown in Fig. 2.

Another feature of the invention is that the friction ring 10 provided by the recess 4 extending as it does below the lowermost wall of the key depression (as seen in Fig. 3) provides for nesting of the lids in the automatic can making machines without interference, hence the keys may be in place on the lids soldered or loose before double seaming of the lids to the can bodies if desired.

From the above description it will be evident that the key may be applied to either end of the can in the manner described, hence my use of the word "lid" in the claims is intended to mean either end of the can.

I claim:

1. A can provided with a depression in a wall thereof adapted to receive an opening key, a key in said depression, said depression

sion provided with a localized area for soldering the key thereto embracing and supporting the key, and the portion of the depression adjacent the localized area being spaced entirely free from the adjacent portions of the key whereby the solder will be localized on said area and be prevented from running along the key.

5. A can provided with a depression in a wall thereof adapted to receive an opening key, a key in said depression, and bosses within the depression supporting the key at opposite ends with the body of the key free of contact with the side walls of the depression, and said key secured at one end only to its supporting boss.

WILFORD E. BURNS.
